UNITED STATES PATENT OFFICE.

JAMES WEIMER, OF SWISSVALE, PENNSYLVANIA, ASSIGNOR OF ONE-HALF
TO SANFORD R. CARSE, OF PITTSBURG, PENNSYLVANIA.

JAM-DOLLY.

No. 856,750.

Specification of Letters Patent.

Patented June 11, 1907.

Application filed November 15, 1906. Serial No. 343,477.

To all whom it may concern:

Be it known that I, JAMES WEIMER, a citizen of the United States of America, residing at Swissvale, in the county of Allegheny and

5 State of Pennsylvania, have invented certain new and useful Improvements in Jam-Dollies, of which the following is a specification, reference being had therein to the accompanying drawing.

10 This invention relates to jam dollies, and the invention has for its primary object to provide an adjustable dolly.

My invention aims to provide a dolly having a novel form of supporting head, and an 15 adjustable die. The supporting head is constructed whereby it may be placed over a rivet head or similar protuberance in direct alinement with the rivet in connection with which the dolly is to be used. The adjustable die permits of the dolly being lengthened or shortened according to the space in which it is to be used, the die being easily and quickly adjusted to accurately position the dolly in order that the rivet which it 20 backs up may be properly operated upon. To this end, I have devised a dolly designed for riveters who have heretofore experienced considerable trouble in properly positioning the dolly and maintaining the same in alinement with the rivet to be operated upon. 25 The construction of the dolly permits of the various parts thereof being readily renewed when worn, without discarding the entire dolly, therefore reducing the expense of maintenance, besides facilitating the work of riveters using a dolly.

The detail construction of my improved dolly will be hereinafter more fully described and then specifically pointed out in the appended claims, and referring to the drawing forming part of this specification, like numerals of reference designate corresponding parts throughout the several views, in which:—

40 Figure 1 is a side elevation of my improved dolly, Fig. 2 is a longitudinal sectional view of the same, Fig. 3 is a detail sectional view of the supporting end thereof, illustrating a slight modification, Fig. 4 is a similar view 45 illustrating another modification, and Fig. 5 is a detail perspective view of a portion of a dolly.

In the accompanying drawing, I have illustrated two sets of beams 1, 1 between

which my improved dolly is mounted, the 55 dolly in the present instance being supported by the rivets 2 of each set of beams.

The dolly comprises a cylindrical body portion 3 having a tapering shank 4 terminating in a bell-shaped end 5 which is cut away as 60 at 6, whereby the end of the dolly may be placed over the head of one of the rivets 2. The cylindrical body 3 at its opposite end is formed with a collar 7, and longitudinally of said body is formed a bore 8 in which is 65 mounted a die 9 having a socket-head 10.

The body 3 of the dolly is provided with diametrically opposed slots 11 intersecting the bore 8, and in said slots slides a key 12, which passes through the end of the die 9. 70 The key 12 prevents the die from becoming detached from the body 3, at the same time permits of its adjustment within the bore 8 of said body.

To adjust the die within the body 3, I employ a wedge-shaped member 14, said member extending through the slots 11 to the bore 8 and engaging the end of the bore 8 and the end of the die 9. The wedge-shaped member 14 is provided with a head 15 and 80 with a key or pin 16, whereby said member cannot become accidentally detached from the body of the dolly.

It will be observed from the novel construction of my improved dolly as just described, that the die 9 can be easily and quickly adjusted by simply tapping upon the head 15 of the member 14, with a hammer or suitable instrument. When the socket-head 10 and the bell-shaped end 5 engage the 90 heads of rivets, the dolly can be readily supported therebetween by driving downwardly upon the member 14 until it has become firmly wedged between the body of the dolly and the end of the die 9. In Figs. 3 and 4, I 95 have illustrated slight modifications, wherein the shank 4 of the dolly is provided with detachable ends 17 and 18, these ends being locked in engagement with the contracted end 19 of the shanks 4 by bolts, keys or pins 100 20. The end 17 corresponds to the bell-shaped end 5 previously described, and it is detachably mounted upon the shank 4 whereby it can be removed and the head 18 placed thereon which is simply a centering 105 end adapted to engage in a beam and hold the dolly stationary while a rivet is being headed or operated upon.

My invention particularly resides in a dolly having an adjustable die, thereby rendering it possible for the die or body of the dolly to be renewed without dispensing with the entire dolly.

I desire it to be understood that such changes in the size, proportion, material and structural details, as are permissible by the appended claims, may be resorted to without departing from the spirit and scope of the invention.

What I claim and desire to secure by Letters Patent, is:—

1. A dolly embodying a body portion having a shank terminating in a bell-shaped end, said end being cut away to permit of the dolly being placed in engagement with a rivet, a die slidably mounted in said dolly body and having a socket-head, a wedge-shaped member mounted between the end

of said die and said dolly body for adjusting said die, means to retain said die within said dolly body, and means to retain said member within said body, substantially as described.

2. A dolly comprising a hollow body at 25 one end and a head on the other end, the hollow portion of said body being slotted transversely, a die slidably-mounted in said hollow end of the body, a pin extending transversely through the slot in the body of 30 the die and holding the latter in the body, and a wedge extending through the slot in the body and engaging the inner end of the die, substantially as described.

In testimony whereof I affix my signature 35 in the presence of two witnesses.

JAMES WEIMER.
